UNITED STATES PATENT OFFICE

128,787

DESIGN FOR A TRAP FOR SNAILS, SLUGS, AND SOW BUGS OR THE LIKE

Bender M. Nelson, Orange County, Calif., assignor
of one-half to Fred H. Albers, Orange, Calif.

Application May 2, 1941, Serial No. 100,741

Term of patent 3½ years

To all whom it may concern:

Be it known that I, Bender M. Nelson, a citizen of the United States, residing in Orange County, State of California, have invented a new, original, and ornamental Design for a Trap for Snails, Slugs, and Sow Bugs or the like, of which the following is a specification, reference being had to the accompanying drawing, forming part thereof.

Fig. 1 is a perspective view of a trap for snails, slugs, and sow bugs, showing my new design;

Fig. 2 is an end elevational view;
Fig. 3 is a side elevational view; and
Fig. 4 is a bottom plan view thereof.

I claim:

The ornamental design for a trap for snails, slugs, and sow bugs or the like, as shown.

BENDER M. NELSON.
